SHAFTLESS CONE CRUSHER AND TILTING MEMBER THEREFOR

Oscar C. Gruender, Milwaukee, Wis., assignor to
Nordberg Manufacturing Company, Milwaukee,
Wis., a corporation of Wisconsin

Application July 28, 1940, Serial No. 347,698

16 Claims. (CL 83—10)

My invention relates to an improvement in gyratory crushers and has for one purpose the provision of a gyratory crusher in which the crusher head is gyrated without the employment of a crushing shaft unitary with the head.

Another purpose is the provision of a head and an actuating structure therefor in which any risk of breakage of the head itself is reduced to a minimum.

Another purpose is the provision of improved means for actuating or gyrating a gyratory crusher head.

Another purpose is the provision of improved means for supporting a gyrated crusher head.

Another purpose is the provision of improved oil sealing means for gyratory crushers.

Another purpose is the provision of a simplified and improved method for producing a satisfactory gyrating movement of a gyratory crusher head.

Other purposes will appear from time to time in the course of the specification and claims.

I illustrate my invention more or less diagrammatically in the accompanying drawings wherein:

Fig. 1 is a vertical axial section;

Fig. 2 is a similar partial section on an enlarged scale; and

Fig. 3 is a detail.

Like parts are indicated by like symbols throughout the specification and drawings.

Referring to the drawings, I illustrate any suitable base or foundation 1, which may be of concrete or the like and which has a central opening 2 aligned with the crusher below described. 3 indicates a circumferential and generally cylindrical main frame which is shown as terminating at its upper end in an outwardly projecting flange 4, having opposite beveled converging faces 5, 6 and a generally horizontal top face 7. A plurality of access apertures 8 are provided in the lower portion of the frame, which may be closed by any suitable plates or closures 9. 10 indicates any suitable radial elements which extend inwardly from the circumferential main frame 3 to a central sleeve structure 11. The central sleeve is outwardly expanded as at 12 and is provided with an aperture as at 13, which receives the inner end 14 of the shaft housing 15. 16 is another enlargement of the shaft housing 15, which penetrates and closes an aperture in the end of an outwardly extending sleeve or enlargement 17, herein shown as formed integrally with the circumferential main frame 3. 18 is an

outer bearing sleeve forming a portion of the shaft housing 15.

Mounted upon the upper edge enlargement 12 of the central sleeve 11 is a supporting structure 5 including an outer member 19 and an inner member 20, the latter being generally aligned with the lower portion of the sleeve 11 and being connected with the member 19 by a horizontal portion 21. This structure may be bolted to the sleeve portion 12 as by any suitable bolts 22. The member 19 has an upwardly and outwardly extending portion 23 which carries a spherical bearing plate or ring 24 defining a sphere, the center of which is indicated at X in Fig. 1.

Resting upon the flange 4 of the main frame is a bowl supporting ring 30 having an inner generally cylindrical portion 31, inwardly screw threaded as at 32. The member 30 has a circumferential channel 33 having faces 5 and 6 engaging the flange 4. Relative rotation of the parts is prevented by any suitable pins 34, having an enlargement 35 positioned between the members 4 and 30. Upward movement of the member 30 is normally prevented by the employment of coil springs 36, which may be nested in and between upper spring abutment members 37 and lower spring abutment members 38. 39 indicate tension members or bolts extending downwardly through the member 30, the upper spring abutments 37 and the lower spring abutments 38. The compression of the springs may be adjusted by varying the location of the nuts 40 at the lower ends of the tension members 39. It will be observed that the upper spring abutments 37 penetrate beneath the flange 4.

Adjustable in the screw threaded portion 31 of the bowl support 30 is a bowl structure including the outer generally cylindrical wall 45, screw threaded as at 46, in mesh with the screw threaded portion 31 of the bowl support 30. Any suitable means not herein shown may be employed with the bowl structure for imparting to it a vertical adjustment. In order to prevent the penetration of dust to the threads 32, 46, 45 I may provide any suitable sealing ring, shown for example in Fig. 3. I illustrate for example a U-shaped ring 40a, which may be secured as by screws 40b to the lower portion of the bowl structure 31, and which receives in its U-shaped aperture any suitable wiping ring 40c of felt or the like. The bowl structure includes a lower upwardly and inwardly inclined wall 47 and an upper downwardly and inwardly inclined wall 48, the two walls converging as shown in Fig. 1. Any suitable wear-taking ring 49 may be provided

for the upper wall 48, and any suitable bowl liner 50 may be employed as a wear-taking crushing element, as shown, having outwardly extending hook-shaped lugs 51 which may be received by the U-shaped locking bolts 52, located in the space between the walls 45, 47 and 48. Since the locking means and the access thereto do not of themselves form part of the present invention, they will not be further described.

53 is any suitable generally cylindrical apron shown as resting upon the top of the bowl. 54 is any suitable forward spout mounted on a structure 55 adjustable on the screw threaded portions of rods 56, which may be suitably mounted upon the crusher.

57 indicates the head or top of a tilting member or actuator shaped like a spherical segment, which has a bottom plane surface 58 and a top spherical surface 59. The plane surface rests on a plane bearing plate or ring 60, herein shown as resting on the portion 21 and having formed integrally with it a cylindrical sleeve 61 located within the member 20. A lower bearing sleeve 62 coaxial with the sleeve 61 is located within the member 11. The two sleeves are concentric but are shown with slightly different diameters. They receive a rotating sleeve 63 having a central gear 64 projecting outwardly into the space within the enlargement 12 and located intermediate the bearing sleeves 61 and 62. The gear 64 is also provided with a counterweight 65 upwardly extending into the space between the members 19 and 20, which may be filled with lead or the like.

67 is a pinion in mesh with the gear 64 and mounted on the drive shaft 68, driven by any suitable pulley 69. The drive shaft is rotatably mounted in bearing sleeves 70, 71 within the portions 15 and 18, as shown in Fig. 1. The sleeve 63 is eccentrically apertured as at 72 to receive a downwardly extending hollow stem 73, herein shown as integral with the top or head 57 of the tilting member. 74 indicates any suitable bearing sleeve located within the eccentric aperture of the sleeve 63. It is to be understood that rotation of the drive shaft 68 rotates the sleeve 63 and imparts an eccentric movement to the stem 73 and the head 57. The axis of the stem is parallel with the axis of rotation of the sleeve 63, and the result is a movement along a horizontal plane, the head 57 resting upon and sliding upon the flat bearing plate 60. Observe that the bottom flat surface 58 of the head is upwardly re-curved adjacent its junction with the hollow stem 73, as at 80, and that the wall of the central aperture of the stem is outwardly curved as at 81 and re-curved as at 82, indicated in Fig. 2, defining a space of substantial content from the top of the head and providing a structure of great strength and with an economy of material. The top of the head may be closed as by any suitable plate 84, and the bottom may be similarly closed as by a plate 85, the two plates being connected by a lubricating tube 86 open at top and bottom. 86a indicates any suitable oil aperture adapted to deliver oil to the bearings 70 and 71.

Resting upon the upper spherical surface of the head 57 is a crusher head generally indicated as 90. It is provided with a bearing plate 91 having a lower concave surface conforming to the spherical convex surface 59 of the tilting member 57. It is to be understood, of course, that it is a matter of choice as to whether the bearing 91 is mounted upon the head or the tilting member, but I find it convenient to mount it on the head, as shown in Figs. 1 and 2, for example by a key or wedge 91a.

The lower portion of the head is provided with a spherical surface 92 adapted to be engaged and to be received by the bearing 24 on the member 23. 93 indicates a crushing mantle which may be thrust down upon the outer conic surface 94 of the head as for example by a thrust member or sleeve 95, which in turn is engaged by a split nut 96 screw threaded as at 97 in relation to a holding sleeve 98, which has an enlarged head 99 located 10 within an aperture of corresponding size within the head. 100 is any suitable lug penetrating a slot 101, whereby relative rotation of the sleeve 98 and the head 99 is prevented. The split nut 97 is held together for example by bolts 97a and is 15 provided with an upwardly and outwardly extending portion 102, upon which any suitable feed limiting or feed distributing plate 103 may be mounted, and may be held in position for example by bolts 104. It will be understood that 20 the above described structure is self-tightening in that the effect of the contact with the crushing material in the crushing cavity defined between the members 50 and 93 is to tighten the split nut and also to direct a lateral thrust in response to 25 the peening of the manganese steel, of which the mantle 93 is formed. When it is desired to release the mantle, however, it is easy to remove the bolts 97a and separate the split nut and thus free the mantle 93 from the securing sleeve 98. 30 I find it useful to provide a wear-taking ring 105 below the lower edge of the mantle 93 to protect a downwardly and outwardly extending lower end 106 of the head. Secured to this lower head 106, as by bolts or screws 107, is an apron 108 having 35 an inwardly extending portion 109 which defines a space 110, which may receive dust or dirt and serve as a retainer until such dirt may be removed by any suitable plugs or closures 111.

Mounted on an inner portion of the apron 108, 40 109 is a spherical surfaced bearing ring 112 concentric with the opposed spherical surface of the member 113. The ring 113 is formed continuously with a generally cylindrical ring 114 slidable along the outer face of the member 19, which is 45 provided with sealing piston rings 115. 116 is a lug downwardly extending from the ring 114, which is positioned in the recess 117 to prevent rotation of the ring 114 about the frame. The structure 113, 114 rests gravitally upon the bearing ring 112 but, to obtain an increased sealing effect, I also spring load it by employing springs 118, the upper ends of which are compressed against the portion 23a of the outwardly extending portion 23 of the member 19, and the lower 55 ends of which are compressed against the bottom of the ring 114. Any suitable housing or guide means for the springs may be employed, as at 119.

In order to return the oil which passes over 60 the outer edge of the bearing 24, I provide a deflector ring 120 which defines a space or small sump 121, connected by passages 122, with a sump or space 123 above the member 23 and exterior of the bearing plate 60, as shown in 65 Fig. 2; thence oil may pass by the passage or passages 124 to the interior of the enlargement 12 of the central main frame portion 11. When lubricating the device, oil may be supplied from any suitable pump not shown, along an oil supply line 125, to the bottom cap 131 of the sleeve structure 11. It passes thence upwardly through the supporting means 132 for the eccentrically apertured sleeves 63, the details of which supporting means are not shown as they do not form 70 part of the present invention. Oil passes up- 75

wardly through the space 72 and through the central oil passage 88 of the tilting device. It then lubricates the bearing surfaces of the members 87 and 81, which may, if desired, be provided with distributing ducts not herein shown. The oil thence reaches the sump 123 and returns to the space within the enlargement 12 and reaches the oil outlet passage 135 and thus returns to the pump by the line 136. Oil also travels along the shaft 68 and reaches the sealing means, which include the housing 137, from which extends another oil return line 138, which communicates with the main oil return line 136.

It will be realized that, whereas I have described and shown a practical and operative device, nevertheless many changes may be made in the size, shape, number and disposition of parts without departing from the spirit of my invention. I therefore wish my description and drawings to be taken as in a broad sense illustrative or diagrammatic, rather than as limiting me to my precise showing.

The use and operation of my invention are as follows:

I illustrate herein a crusher in which a generally conic crusher head 90 is gyrated within a normally fixed crushing bowl 50, the bowl overhanging the head, and the opposed mantle 93 the bowl liner 50 having generally conical surfaces which define a crushing cavity. It has been past practice to employ a crushing head of this general type in which an integral downwardly extending shaft is seated within eccentric apertures of a rotated sleeve. Breakage of both head and shaft is not infrequent and causes expense of replacement and delays for replacement and repair which reduce the efficiency of the machine. In addition, in the earlier machine, the bore within the eccentric had its center line at an angle, with the center line of the outer diameter of the eccentric. It will be noticed that in the structure of the present application the center line of the eccentric is parallel with the center line of the crusher.

In my invention I provide a crushing head and means for supporting and actuating it, which eliminates the breakable downwardly extending shaft, and in which the crushing thrust against the head is directly against a supporting means, so that any tendency of any part of the head to break under crushing stress is greatly reduced.

Referring for example to Fig. 1, in the operation of the device the rotation of the shaft 68 rotates the eccentrically apertured shaft 63 about a preferably vertical axis. The shaft 68 is provided with an eccentric aperture which also has preferably a vertical axis. In this aperture is received a downwardly extending shaft 73, which is shown as integral with or rigidly secured to the tilting member 57. The tilting member has a flat lower surface 58 which operates in a horizontal plane on the bearing plate 60. It has a spherical upper surface 59 described about the center A of Figs. 1 and 2, which engages a conforming spherical surface of the bearing member 91 of the head 90. An outer spherical bearing 24, concaved oppositely to the bearing for the element 21 and contacting a cooperative spherical bearing on the head 90, aids in guiding the head, particularly at no-loads, with the result that the eccentric movement of the tilting member 57, in response to rotation of the drive shaft 68, produces a gyratory wobble of the head 90. The spherical bearing 24 is described about the center X of Fig. 1. In effect, there is a point

of close approach of the head 90 toward the bowl, which passes circumferentially around the crushing cavity as the head 90 is turned eccentrically.

5 The crushing thrust in the cavity, defined by the members 90 and 93, is received first by the head and then by the tilting member 57, and is transmitted to the central portion of the main frame along the bearing sleeve 60, and also along the bearing sleeve 24. There is no overhanging of the free unsupported part of the head which is subjected to crushing stress. Nor is there any depending shaft which is subjected to bending moment.

10 15 The machine is easily disassembled for repair or replacement. The whole structure can be readily upwardly removed. Thereafter, by releasing the bolts 97a, the split sleeve 96 is released and the mantle 93 and the pressure sleeve 95 may be upwardly lifted from the head. A readily removable securing means is important with the use of the crushing members formed of manganese steel. It is a characteristic of this material that it will peen or spread under crushing stress and tend to apply such pressure against any locking means employed as to make it hard to remove them. However, once the screws 97a are released, and they can be, for example, burned off with a blowtorch, the split sleeve 96 can be easily opened and the entire device disassembled.

20 25 30 35 40 45 50 It will be observed that the bowl, including the bowl liner 50, is normally fixed and has no motion except when the presence of an uncrushable mass of material in the crushing cavity causes the bowl to rise against the thrust of the spring 36, in response to the movement of the head toward the bowl in the course of the crushing nip. The head is a part of the gyratory movement about the center "X," as shown in Fig. 1. The material passes through the crushing cavity under gravity. In order to permit this gravitational feed, it is necessary that the angle of the head approximate the angle of repose of the material being crushed. It may, for example, have an angle of the order of forty degrees from the horizontal, but the angle may vary in different machines and in different sizes of machines. It is essential, however, that the angle be sufficiently high to prevent particles from resting upon the head and to insure that they move gravitally downwardly through the crushing cavity at all times, unless they are actually gripped between the opposed crushing members.

55 I claim:

1. For use in a gyratory crusher having a normally fixed bowl, a crushing head including a generally conic body portion having a crushing face of an angle higher than the angle of repose of the material delivered thereto, said body portion being penetrated upwardly from below by an aperture of substantial depth in relation to its transverse diameter, said aperture being defined by a downwardly concave generally spherical surface, and actuating means for said head including a tilting member and means for gyrating it, said tilting member having a tilting head with an upwardly convex spherical surface conforming to the spherical surface in the bottom of the head, said head having a downwardly convex spherical bearing surface adjacent the lower outer edge thereof, the center of said surface being located above the top of the crushing portion of the head, and a normally fixed support for said head including an upwardly concave spherical bearing element adapted to receive and

conform to said downwardly convex spherical bearing surface of the crushing head.

2. For use in a gyratory crusher having a normally fixed bowl, a generally conic truncated crushing head, the conic face of which is of an inclination higher than the angle of repose of material fed thereto, a cavity extending upwardly into the bottom of said head, said cavity being defined by a generally spherical surface, an axial aperture in said head, a stem extending upwardly through said aperture a substantial distance above the top of the head, and an enlargement at the lower end of said stem, the bottom of said head being recessed to receive said enlargement, a conic mantle mounted upon the exterior surface of the head, a thrust member upon said stem, adapted to be opposed to the upper edge of said mantle, compression means on said stem adapted to urge said thrust member against the upper edge of the mantle, and a laterally extending feed plate mounted on the top of said stem.

3. For use in a gyratory crusher having a normally fixed bowl, a generally conic truncated crushing head, the conic face of which is of an inclination higher than the angle of repose of material fed thereto, a cavity extending upwardly into the bottom of said head, said cavity being defined by a generally spherical surface, an axial aperture in said head, a stem extending upwardly through said aperture a substantial distance above the top of the head, and an enlargement at the lower end of said stem, the bottom of said head being recessed to receive said enlargement, a conic mantle mounted upon the exterior surface of the head, a thrust member upon said stem, adapted to be opposed to the upper edge of said mantle, compression means on said stem adapted to urge said thrust member against the upper edge of the mantle, and a laterally extending feed plate mounted on the top of said stem, and means for preventing relative rotation of stem and head.

4. For use in a gyratory crusher having a normally fixed bowl, a generally conic truncated crushing head, the conic face of which is of an inclination higher than the angle of repose of material fed thereto, a cavity extending upwardly into the bottom of said head, said cavity being defined by a generally spherical surface, an axial aperture in said head, a stem extending upwardly through said aperture a substantial distance above the top of the head, and an enlargement at the lower end of said stem, the bottom of said head being recessed to receive said enlargement, a conic mantle mounted upon the exterior surface of the head, a thrust member upon said stem, adapted to be opposed to the upper edge of said mantle, compression means on said stem adapted to urge said thrust member against the upper edge of the mantle, and a laterally extending feed plate mounted on the top of said stem, said head having adjacent its bottom a downwardly convex spherical bearing surface surrounding said cavity, the center of said surface being located adjacent the top of the head.

5. For use in a gyratory crusher having a normally fixed bowl, a generally conic crushing head having a conic upper and outer surface of an inclination higher than the angle of repose of the material fed thereto, said head having a cavity extending upwardly into the bottom of the head and a bearing liner fixed in said cavity, said liner having a generally spherical downwardly concave annular bearing surface, said crushing head being truncated and having a stem removably se-

cured thereto and extending upwardly through the center of said truncated portion, a mantle mounted on the exterior conic surface of the head, and means associated with said stem for thrusting said mantle downwardly against said head.

6. For use in a gyratory crusher having a normally fixed bowl, a generally conic crushing head having a conic upper and outer surface of an inclination higher than the angle of repose of the material fed thereto, said head having a cavity extending upwardly into the bottom of the head and a bearing liner fixed in said cavity, said liner having a generally spherical downwardly concave annular bearing surface, said crushing head being truncated and having a stem removably secured thereto and extending upwardly through the center of said truncated portion, a mantle mounted on the exterior conic surface of the head, and means associated with said stem for thrusting said mantle downwardly against said head, including a sleeve having a conic portion conforming generally to the conic surface of the mantle.

7. For use in a gyratory crusher having a normally fixed bowl, a generally conic crushing head having a conic upper and outer surface of an inclination higher than the angle of repose of the material fed thereto, said head having a cavity extending upwardly and inwardly into the bottom of the head and having a generally annular spherical downwardly concave bearing surface thereabout, said head having an axial aperture extending upwardly therethrough, a stem extending upwardly through said aperture and having an enlarged lower portion interfitting with an enlarged lower portion of said aperture, a mantle mounted on the exterior conic surface of the head, and means associated with said stem for thrusting the mantle downwardly against said head and for thereby holding the mantle normally fixed in position.

8. For use in a gyratory crusher having a normally fixed bowl, a generally conic crushing head having a conic upper and outer surface of an inclination higher than the angle of repose of the material fed thereto, said head having a cavity extending upwardly and inwardly into the bottom of the head and having a generally annular spherical downwardly concave bearing surface thereabout, said head having an axial aperture extending upwardly therethrough, a stem extending upwardly through said aperture and having an enlarged lower portion interfitting with an enlarged lower portion of said aperture, a mantle mounted on the exterior conic surface of the head, and means associated with said stem for thrusting the mantle downwardly against said head and for thereby holding the mantle normally fixed in position, the stem being removable downwardly through said aperture.

9. For use in a gyratory crusher having a normally fixed bowl, a generally conic crushing head having a conic upper and outer surface of an inclination higher than the angle of repose of the material fed thereto, said head having a cavity extending upwardly and inwardly into the bottom of the head and having a generally annular spherical downwardly concave bearing surface thereabout, said head having an axial aperture extending upwardly therethrough, a stem extending upwardly through said aperture and having an enlarged lower portion interfitting with an enlarged lower portion of said aperture,

a mantle mounted on the exterior conic surface of the head, and means associated with said stem for thrusting the mantle downwardly against said head and for thereby holding the mantle normally fixed in position, and means for normally preventing relative rotation of head and mantle.

10. For use in a gyratory crusher having a normally fixed bowl, a generally conic truncated crushing head having a conic upper and outer surface of an inclination higher than the angle of repose of the material fed thereto, said head having a coaxial central spherical bearing cavity extending upwardly into the bottom of the head and of a maximum diameter greater than that of the truncated part of the head, the center of sphericity of said cavity being located substantially below said head, said head having a downwardly convex spherical bearing surface about a lower portion thereof surrounding said first cavity, the center of sphericity of said downwardly convex bearing surface being located above the top of the crushing cavity defined by said head, said head having a stem removably secured thereto and extending upwardly from the center of the truncated portion.

11. For use in a gyratory crusher having a normally fixed bowl, a generally conic truncated crushing head having a conic upper and outer surface of an inclination higher than the angle of repose of the material fed thereto, said head having a coaxial central spherical bearing cavity extending upwardly into the bottom of the head and of a maximum diameter greater than that of the truncated part of the head, the center of sphericity of said cavity being located substantially below said head, said head having a downwardly convex spherical bearing surface about a lower portion thereof surrounding said first cavity, the center of sphericity of said downwardly convex bearing surface being located above the top of the crushing cavity defined by said head, said head having a stem removably secured thereto and extending upwardly from the center of the truncated portion, the lower end of said stem extending into said head and terminating adjacent the top of said bearing cavity.

12. For use in a gyratory crusher having a normally fixed bowl, a generally conic truncated crushing head having a conic upper and outer surface of an inclination higher than the angle of repose of the material fed thereto, said head having a coaxial central spherical bearing cavity extending upwardly into the bottom of the head and of a maximum diameter greater than that of the truncated part of the head, the center of sphericity of said cavity being located substantially below said head, said head having a downwardly convex spherical bearing surface about a lower portion thereof surrounding said first cavity, the center of sphericity of said downwardly convex bearing surface being located above the top of the crushing cavity defined by said head, said head having a stem removably secured thereto and extending upwardly from the center of the truncated portion, and a sealing apron extending downwardly from a lower portion of said head, said sealing apron having an upwardly concave spherical bearing surface concentric with the downwardly convex bearing surface about the lower portion of the head, and of greater radius.

13. For use in a gyratory crusher having a normally fixed bowl, a generally conic truncated

crushing head having a conic upper and outer surface of an inclination higher than the angle of repose of the material fed thereto, said head having a coaxial central spherical bearing cavity extending upwardly into the bottom of the head and of a maximum diameter greater than that of the truncated part of the head, the center of sphericity of said cavity being located substantially below said head, said head having a downwardly convex spherical bearing surface about a lower portion thereof surrounding said first cavity, the center of sphericity of said downwardly convex bearing surface being located above the top of the crushing cavity defined by said head, said head having a stem removably secured thereto and extending upwardly from the center of the truncated portion, and a sealing apron extending downwardly from a lower portion of said head, said sealing apron having an upwardly concave spherical bearing surface concentric with the downwardly convex bearing surface about the lower portion of the head, and of greater radius, and having a sump located at a level below said upwardly concave surface.

14. For use in a gyratory crusher having a normally fixed bowl, a crushing head including a generally conic body portion having a crushing face of an angle higher than the angle of repose of the material delivered thereto, said body portion being penetrated upwardly from below by an aperture of substantial depth in relation to its transverse diameter, said aperture being defined by a downwardly concave generally spherical surface, and actuating means for said head including a tilting member and means for gyrating it, said tilting member having a tilting head with an upwardly convex spherical surface conforming to the spherical surface in the bottom of the head, said head having a downwardly convex spherical bearing surface adjacent the lower outer edge thereof, the center of said surface being located above the top of the crushing portion of the head, and a normally fixed support for said head including an upwardly concave spherical bearing element adapted to receive and conform to said downwardly convex spherical bearing surface of the crushing head, said head having a sealing apron extending downwardly from a lower portion thereof, said sealing apron having an upwardly concave spherical bearing surface concentric with said downwardly convex spherical bearing surface but of greater radius, and an opposed, conforming, downwardly convex wiping member movably mounted in relation to said fixed support.

15. For use in a gyratory crusher having a normally fixed bowl, a crushing head including a generally conic body portion having a crushing face of an angle higher than the angle of repose of the material delivered thereto, said body portion being penetrated upwardly from below by an aperture of substantial depth in relation to its transverse diameter, said aperture being defined by a downwardly concave generally spherical surface, and actuating means for said head including a tilting member and means for gyrating it, said tilting member having a tilting head with an upwardly convex spherical surface conforming to the spherical surface in the bottom of the head, said head having a downwardly convex spherical bearing surface adjacent the lower outer edge thereof, the center of said surface being located above the top of the crushing portion of the head, and a normally fixed support for said head including an upwardly concave spherical

bearing element adapted to receive and conform to said downwardly convex spherical bearing surface of the crushing head, said head having a sealing apron extending downwardly from a lower portion thereof, said sealing apron having an upwardly concave spherical bearing surface concentric with said downwardly convex spherical bearing surface but of greater radius, and an opposed, conforming, downwardly convex wiping member movably mounted in relation to said fixed support, said sealing apron having a sump located at a level below said upwardly concave bearing surface.

16. For use in a gyratory crusher having a normally fixed bowl, a generally conic truncated crushing head having a conic upper and outer surface of an inclination higher than the angle

5 of repose of the material fed thereto, said head having a coaxial central spherical bearing cavity extending upwardly into the bottom of the head and of a maximum diameter greater than that of the truncated part of the head, the center of sphericity of said cavity being located substantially below said head, said head having a downwardly convex spherical bearing surface about a lower portion thereof surrounding said first cavity, the center of sphericity of said downwardly convex bearing surface being located above the top of the crushing cavity defined by said head, said head having a stem secured thereto and extending upwardly from the center of the truncated portion.

10
